(57) **CLAIM**

The ornamental design for an earphone as shown and described.

DESCRIPTION

FIG. 1 is a front, top, left side perspective view of an earphone showing the new design;

FIG. 2 is a rear, bottom, right side perspective view of the earphone;

FIG. 3 is a front elevational view of the earphone;

FIG. 4 is a rear elevational view of the earphone;

FIG. 5 is a top plan view of the earphone;

FIG. 6 is a bottom plan view of the earphone;

FIG. 7 is a right side elevational view of the earphone;

FIG. 8 is a left side elevational view of the earphone; and,

FIG. 9 is an enlarged partial cross-sectional view of the earphone taken in the direction of line 9-9 of FIG. 3 with the internal system omitted.

Portions of the drawings shown in broken lines form no part of the claimed design. The dot-dash lines define a boundary of the claimed design and form no part of the claimed design.

1 Claim, 9 Drawing Sheets
